ARROWHEAD

Leonard E. Blanchette, Cudahy, Edmund T. Ortis, South Milwaukee, and Stanley H. Wanserski, Cudahy, Wis.

Application February 1, 1955, Serial No. 485,364

3 Claims. (Cl. 273—106.5)

Our invention relates to improvements in heads for archery arrows.

The primary object of our invention is to provide an arrowhead with means adapted to prevent an arrow shaft from sliding through high grass, foliage, or brush and thereby becoming lost therein.

Another object is to provide an arrowhead with means for the above purpose which will reduce the tendency of the arrow shaft to break by whipping when the shaft is shot into wood, or the like.

Still another object is to provide an arrowhead with means for accomplishing the above and which will catch in grass or foliage, also brush, so that the shaft will tilt into a slanting or upright position in which it may be easily seen for retrieving.

Yet another object is to provide an arrowhead for increasing the effectiveness of an arrow in striking small animals, particularly, at one side of the line of flight of the shaft.

These together with other objects and advantages which will become subsequently apparent reside in the details of construction and operation as more fully hereinafter described and claimed, reference being had to the accompany drawings forming a part hereof, wherein like numerals refer to like parts throughout, and in which:

Figure 1 is a view in plan, partly broken away, of an arrow shaft equipped with our improved arrowhead in the preferred embodiment thereof;

Figure 2 is a view in front elevation of the same; and Figure 3 is a view in longitudinal section taken on the line 3—3 of Figure 2.

Referring to the drawing by numerals, 1 designates a conventional arrow shaft having the usual flights 3 and nock 5, and provided with our improved arrowhead designated generally by the numeral 7.

The arrowhead 7 comprises a cylindrical ferrule 9 having a tapered axial bore 11 blind at the front end of the ferrule and by means of which said ferrule is detachably fitted with a wedge fit over a tapered leading end 13 on the shaft 1. A circumferential flange 15 is formed on the front end of the ferrule 9 for a purpose presently seen. Preferably, the ferrule 9 is formed of aluminum for lightness in weight and requisite strength.

A plurality of forwardly opening, spring steel, wire hooks 17 are carried by the flange 15 and grouped around the ferrule 9 in 120° angular relation. The hooks 17 are preferably formed with U-bends 19 lying in the rear of the flange 15 in planes radial to the ferrule 9, and hence, to the shaft 1, and which are sharp pointed, as at 21, said hooks being provided with shanks 23 extending forwardly of the ferrule 9 through openings 24 in the flange 15 in which said shanks are tightly fitted. The shanks 23 are bent to provide portions 25 converging forwardly of the flange 15 to prevent rearward slipping of said shanks in said flange and forwardly of said portions 25, the shanks 23 are bent to provide straight close together parallel, front portions 27 grouped side-by-side equidistantly around the axis of the ferrule 9 and the

2

shaft 1 and brazed together, as at 27 to form a leading reduced stem on said shaft.

A conical hollow, terminal tip 31 of metal, sharp pointed and having a barb 33 thereon caps the front ends 5 of the shanks 23 and is suitably secured thereto.

As will now be seen, when the shaft 1 is in flight and enters grass, foliage, or brush, the bends 19 of the hooks 17 will catch into such growths and stop the flight of the shaft before it is hidden from view and lost. Also, the bends 19 of the hooks 17 will tend to tilt the shaft 1, particularly in grass, into upright positions so that the shaft may readily be seen, in grass or other growths, and particularly in long grass. The points 21 of the bends 19, which is to say the hooks 17, will snag and penetrate game missed by the tip 31. Because of the resiliency of the wire hooks 17, at the shanks 23, when the tip 31 penetrates wood, or the like, tendency of the shaft 1 to snap or break will be greatly reduced as a result of whipping of the shaft. The same is true when the point 20 21 of a bend 19 penetrates wood or similar material.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the appended claims.

What is claimed as new is as follows:

1. An arrow construction comprising, in combination, an archery arrow shaft and an arrow head construction for the leading end of said shaft comprising a plurality of complemental approximately J-shaped hooks each having a shank portion and a U-bend defining a hook having a terminal bill portion, the shank portions being grouped together and the leading ends being linearly straight, parallel, and fixed to each other, the intermediate portions being bent outwardly into divergent relationship and being spaced from each other in circumferentially equi-distant relationship, an axially disposed penetrating tip fixedly secured to the leading ends of said straight shank portions, and a hub-like ferrule fitting over the leading end of the shaft and lodged in the space between said divergent shank portions.

2. The structure defined in claim 1 and wherein said ferrule is of cap-like form and is provided at its forward closed end with an outstanding flange, said flange having circumferentially spaced holes and portions of the shank portions passing through said holes.

3. An arrowhead comprising a ferrule adapted to fit over the leading end of an archery arrow shaft, a plurality of forwardly opening hooks grouped around said ferrule equi-distantly and carried thereby, said hooks having shanks comprising straight parallel portions extending forwardly of said ferrule side by side and grouped close together around the axis of the shaft in connected together relation to form a leading stem on said shaft, and a sharp pointed, terminal tip fixed on said portions and extending forwardly thereof, said ferrule having a circumferentially apertured flange, said shanks extending forwardly through said flange, and having bent portions extending rearwardly from said straight portions to the flange for preventing said shanks from working rearwardly in the flange, said tip being hollow and capping said shanks.
